UNITED STATES PATENT OFFICE

1,998,333

MANIFOLDING DEVICE

William C. Pfeiffer, Dayton, Ohio, assignor to The Egry Register Company, Dayton, Ohio, a corporation of Ohio

Application December 22, 1932, Serial No. 648,365

4 Claims. (Cl. 197—126)

My invention relates to manifolding devices and a method of handling paper sheets and interleaved carbon sheets.

It is my object to provide a continuous feed of a plurality of strips of paper into a typewriting machine which may be written upon and torn off in given lengths while employing the same carbon sheets between successive lengths of the main paper sheets that are written upon.

10 It is my object to provide a mechanism and method by which the carbon sheets and paper sheets are written upon and move forwardly as the writing operation takes place until it is completed; then the carbon and paper sheets 15 are moved backwardly by having their rear ends lifted by hand upon release from the platen; thereafter, the carbon sheets are held in their uppermost position while the paper sheets are fed forwardly without the carbons to the tear-off position and are there torn off; whereupon 20 the carbon sheets are released and are moved forwardly with a new group of paper sheets for another writing operation.

Referring to the drawings:

25 Figure 1 is a perspective of the paper sheets and carbon sheets in writing position in a typical typewriting machine;

Figure 2 is a perspective of the holder for the carbon sheets with the paper sheets interleaved 30 therebetween;

Figure 3 is a front elevation of the attachment of my invention with the carbon support at the lowermost point on the machine;

Figure 4 is a side elevation of the attachment; 35 Figure 5 is a side elevation of the attachment with the paper aligning pins elevated and the carbon holder pin in operation;

Figure 6 is a detail side elevation of the paper aligning pins and their support in operative position;

40 Figure 7 is a similar view with the pins thrown in inoperative position;

Figure 8 is a section on the line 8—8 of Figure 10;

45 Figure 9 is a side elevation from the right hand side of Figure 10;

Figure 10 is a front elevation of the attachment with the carrier in its uppermost position;

Figure 11 is a section on the line 11—11 of 50 Figure 10 showing the parts in position ready to write;

Figure 12 is a similar view showing the parts after the paper and carbons have been written upon;

55 Figure 13 is a detail front elevation of one cor-

ner of the carrier showing how it is held against movement by the stop pin;

Figure 14 is a section on the line 14—14 of Figure 13 showing the arrangement of the interleaved carbons and their method of support;

5 Figure 15 is a section on the line 15—15 of Figure 13 showing the stop pin in full lines in inoperative position;

Figure 16 is a similar view showing the stop pin in operative position;

10 Figure 17 is a front elevation of the attachment with the paper and carbon sheets in position showing the sheets that have been written upon about to be torn off without the carbons, the carbons being held in their uppermost position;

Figure 18 is a section on the line 18—18 of Figure 17;

15 Figure 19 is a section on the line 19—19 of Figure 18;

Figure 20 is a section on the line 20—20 of Figure 19;

20 Figure 21 is a detail sectional view of a modified form of holding pin;

25 Referring to the drawings in detail, 1 is a typewriting machine having a platen 2 and a pressure roller 3 which is releasable in the usual manner by a suitable hand lever. 4 indicates the type face which engages with the paper sheets to write upon them.

30 Mounted upon the typewriter and above the typewriter is the attachment of my invention comprising yoke members 5 which are mounted upon the side frame of the typewriter and held in position by the latch members 6. Any form of mounting may be employed that is desired. This attachment comprises side frame members

35 7 which are connected at their lower ends by the cross frame member 8 and at their tops by the cross frame member 9. This forms a rectangular frame made of plates or angles. On the top frame member 9 is a pair of spaced brackets 10 carrying the axle 11 having the guide sheaves 12 over which the strips of paper are fed from the supply of paper on a roll or pack 40 as at 13. Diagonal brace members 14 are connected at their ends by the cross frame members 8 and 9 and intermediate their ends at 15.

The side frame members 7 carry at the top and bottom transverse axles 16 and 17 respectively having sprocket wheels 18 carrying the side chains 19. To these side chains is attached at 20 the side bar 21 which has bifurcated ends 22 engaging and guided by the side frame members 7. This side bar 21 carries a back plate 22a 45

50

55

on which is hinged at 23 the frame 24 having the paper aligning and holding pins 25 which are adapted to enter the file punch holes 26 in the paper sheets and in similar holes 27 in the back plate so that the paper sheets are firmly aligned and held so as to cause them to travel with the carriage when actuated by the side chains 18.

Mounted on the face of the back plate 22 over the cross frame slide bar 21 is a pair of spaced notched studs 28 which carry a plurality of strips 29 having holes 30. These strips each carry a depending carbon sheet 31 adapted to be interleaved between the paper strips 32, 33, 34 and 35. A spring plate 36 slotted at its ends at 37 is adapted to be mounted in the notches 38 in the pins 28 in order to hold the several sheets in position on the carbon carrier. Thus, while the pins 25 are in the holes 26 and 27 carbon sheets and paper strips travel together with the slide bar 21. When the pins 25 are removed as indicated in Figure 5 by the lifting of the lever 39 on the pivot 40 through the thumb piece 41 then the paper strips are permitted to move independently of the carbon sheets. To prevent the carbon sheets moving with the paper sheets I have provided on the lever 39 a finger 42 which extends over the outside of one of the side frame members 7 beneath it and inside of it so as to project through the hole 43 in the side frame member 7 and thus interpose its nose 44 in the path of the side bar 21 to prevent the side bar moving with the chains and to prevent the chains from moving and to prevent the carbon sheets from moving while permitting the paper strips to move over the carbon sheets freely as in the case when it is desired to move the strips through the machine after having been written upon without the carbon sheets to the tear-off position where they can be torn off.

In order to insure that the chains will move in unison I have provided a cross frame member 45 which is attached to the chains at 46 and is guided by the vertical guide members 47 that are connected to the upper and lower frame members 8 and 9. This insures uniformity of movement of the two chains. This member 45 also acts as a counter weight.

Method of operation

The sequence of operations is as follows: Starting with the frame in its uppermost position as in Figure 10 the carbon sheets are interleaved with the paper strips in their ready-to-write position shown in Figure 12. The pressure roller 3 is engaging the strips and the strips are engaging the platen. The ends of the carbon sheets are indicated at 48 while the ends of the paper strips are indicated at 49 and the file punch holes in the free ends of the sheets formed from the strips are indicated at 50. As the typewriter rides and the platen turns the carbon sheets and paper strips are moved through the machine and the carriage for the carbon sheets and paper strips moves downwardly as indicated in Figure 1 until it finally reaches the position indicated in Figure 12 when the writing operation is completed.

The next problem is to get the carbon sheets from between the papers into a new writing position and to tear off the written sheets from the paper strips without tearing off the carbon sheets. To do this, the operator places his thumb or other finger beneath the bar 21 as at 51 and, at the same time, releases the pressure roller 3. By lifting on the bar 21 the paper strips and

carbon sheets are returned to their initial position. Then the operator presses the lever 39 at 41 thereby removing the pins 25 from the holes 26 and 27 and inserts the pin 42 in the hole 43 so as to hold the carriage 21 from downward movement thereby holding the carbon sheets stationary while releasing the paper strips. The pressure roller 3 is again engaged with the paper strips and the platen is turned forwardly feeding out the paper sheets that have been written upon until they come to their tear-off position as indicated in Figures 17 and 18 whereupon the tearing-off operation takes place along the line indicated at 52. Then the lever 39 is released, the pins 25 enter a new set of holes 26 and the carbon sheets and paper strips are fed forwardly to the writing position as heretofore described.

Referring particularly to Figures 6 and 7, it will be noted that the swinging frame 24 is yieldingly held so that the pins 25 are normally in engagement with the paper strips by reason of the spring 24a. But, if it is desired to completely detach the pins and render the frame 24 inoperative the frame may be thrown over dead center of the pivot 23 and the spring 24a will hold it in that position so that the strips may be adjusted freely without respect to the pins 25.

It will be understood that I desire to comprehend within my invention such modifications as may be necessary to adapt it to varying conditions and uses.

Having thus fully described my invention, what I claim as new and desire to secure by Letters Patent, is:

1. A new article of manufacture for use as a carbon carrier comprising a frame, a sliding carrier for carbon sheets guided thereby, means to actuate said carrier as it is guided by the frame, means to guide a plurality of paper strips over said carrier, means on said carrier for aligning the paper strips and connecting them therewith, means of detachably supporting a plurality of carbon sheets, a lever pivoted on said frame, a pin carried by said lever adapted to arrest the movement of said carrier, and means on said lever for detaching the paper strips from said carrier.

2. In combination, a frame, spaced axles carrying sprockets and chains on their side thereof, a carrier comprising a transverse member guided by said frame and carried by said chains, a frame pivoted on said carrier having aligning pins entering paper strips and holes in the carrier, spaced studs adapted to carry carbon supports mounted on said carrier, a lever pivoted on said frame adapted to engage said pins and disengage them from the paper strips, means simultaneously operated by said lever for engaging the carrier to arrest its movement.

3. In combination, a frame, spaced axles carrying sprockets and chains on their side thereof, a carrier comprising a transverse member guided by said frame and carried by said chains, a frame pivoted on said carrier having aligning pins entering paper strips and holes in the carrier, spaced studs adapted to carry carbon supports mounted on said carrier, a lever pivoted on said frame adapted to engage said pins and disengage them from the paper strips, means simultaneously operated by said lever for engaging the carrier to arrest its movement, and an axle mounted on the top of said frame having guide wheels thereon for guiding paper strips to said carrier.

4. In combination, a frame, spaced axles carry-

ing sprockets and chains on their side thereof, a carrier comprising a transverse member guided by said frame and carried by said chains, a frame pivoted on said carrier having aligning pins entering paper strips and holes in the carrier, spaced studs adapted to carry carbon supports mounted on said carrier, a lever pivoted on said frame

adapted to engage said pins and disengage them from the paper strips, means simultaneously operated by said lever for engaging the carrier to arrest its movement, a counter weight mounted on said chains, and means for guiding said counter weight.

5

WILLIAM C. PFEIFFER.
